UNITED STATES PATENT OFFICE.

CHARLES H. EDER, OF CHICAGO, ILLINOIS.

BOTTLE-STOPPER.

1,052,228.

Specification of Letters Patent.

Patented Feb. 4, 1913.

Application filed October 5, 1911. Serial No. 652,952.

To all whom it may concern:

Be it known that I, CHARLES H. EDER, a citizen of the United States, residing at Chicago, in the county of Cook and State 5 of Illinois, have invented new and useful Improvements in Bottle-Stoppers, of which the following is a specification, reference being had to the accompanying drawings, forming a part thereof.

10 The purpose of this invention is to provide an improved form of stopper or cap, adapted for use in connection with bottles, collapsible tubes and the like.

It consists of the features and elements 15 described and shown in the drawings as indicated in the claims.

In the drawings: Figure 1 is a side elevation of a collapsible tube fitted with a cap embodying this invention. Fig. 2 is an elevation of the same partly in section, as indicated at the line, 2—2, on Fig. 1. Fig. 3 is a sectional view showing the cap in open position. Fig. 4 is a top plan view of the tube with cap in closed position, but not 25 rotated to locked position. Fig. 5 is a top plan view of the tube with cap in closed and locked position.

The stopper, or cap, which is the subject of this invention, while readily adaptable 30 to serve for the closure of bottles or other receptacles, is shown as applied to the usual form of collapsible tube having a body, 1, made of soft metal which may be compressed to effect the discharge of its contents 35 through the aperture, or throat, 2, of the neck, 3. This neck, 3, is preferably constructed of material somewhat tougher and thicker than that of the body, 1, such that recesses, 3^a, may be formed in it to serve as 40 pivot journals for the bent ends of the wire loop, 4, by which the cap, 5, is held in position. The end of the neck, 3, is preferably rounded off at 3^b so as to approximate in form a segment of a sphere, and the cap, 5, 45 is made spherically concave with about the same curvature at its under side. Thus a reasonable amount of pressure applied to hold the cap against the spherical end of the neck, 3, will serve to effect perfect closure 50 of the aperture, 2; and if the curvature of the cap be made slightly greater than that of the end of the neck, 3, it will be even more certain to be properly seated against the rim of the aperture, 2. The desired 55 pressure between the cap, 5, and the spherical end of the neck, 3, is secured by form-

ing in the top surface of the cap a diametrical groove or valley, 5^a, and by so dimensioning the wire loop, 4, that when this valley stands in registration with the wire, 60 as shown in Fig. 4, the cap, 5, will be only loosely held against the end of the neck, 3. Then by rotating the cap, 5, to the position shown in Fig. 5, so as to bring a thicker portion thereof against the wire loop, 4, 65 the cap may be securely bound upon the rounded end of the neck, 3, and the aperture, 2, will be effectively closed. The top surface of the cap, 5, is sloped upward to both sides of the valley, 5^a, with the same inclination so that rotation of the cap in either direction from the position illustrated in 70 Fig. 4 will accomplish the desired closure of the aperture, 2, regardless of whether the operator be right-handed or left-handed. 75 The cap, 5, is centered for rotation with respect to the wire loop, 4, by the lodgment of a bend, 4^a, in the loop in the recess, 5^b, formed in the upper surface of the cap at 80 its center.

For uncovering the mouth or aperture of the tube, it is only necessary to rotate the cap so as to bring its valley, 5^a, into registration with the wire, 4, as shown in Fig. 4; the pressure between the cap and the tube 85 being thus released, the cap may be readily swung to one side of the aperture, 2, about the pivotal ends of the loop, 4, to a position shown in Fig. 3. For insuring correct centering of the cap over the end of the tube 90 when it is swung back for closure thereof, a pair of lugs, 3^c, are formed on the sides of the neck, 3, and provided with vertical grooves into which the lateral portions of the loop, 4, may be snapped as the loop 95 assumes its vertical position.

I claim:

1. In combination with a receptacle having a hollow body, and an apertured neck extending therefrom, the end of said neck 100 being spherically rounded, a concave cap adapted to be seated upon the rounded end of said neck, a wire loop extending from the neck over the cap, the cap being of different thicknesses at its different axial sections and being adapted to be rotated about its axis for securement between the loop and the end of the neck, and the loop being pivotally secured to the neck for 105 swinging across the end thereof.

2. In combination with a receptacle having a hollow body, and an apertured neck

extending therefrom, the end of said neck being spherically rounded, a concave cap adapted to be seated upon the rounded end of said neck, a wire loop extending from the neck over the cap, the cap being of different thicknesses at its different axial sections and being adapted to be rotated about its axis for securement between the loop and the end of the neck, the loop being pivotally secured to the neck for swinging across the end thereof, and the cap being swivelly engaged by the loop.

3. In combination with a receptacle having a hollow body and an apertured neck extending therefrom, the end of said neck being spherically rounded, a concave cap adapted for seating upon the rounded end of said neck, a wire loop extending from the neck over the cap, said cap being of different thicknesses at its different axial sections and being rotatable about its axis for securement between the loop and the end of the neck, the loop being pivotally secured to the neck for swinging across the end thereof, the outer face of the cap having a central depression, and the loop being bent into said depression for swivelly engaging the cap.

4. In combination with a receptacle having a hollow body and an apertured neck extending therefrom, the end of said neck being spherically rounded, a concave cap adapted for seating upon the rounded end of said neck, a wire loop extending from the neck over the cap, said cap being of different thicknesses at its different axial sections and being rotatable about its axis for se-

curement between the loop and the end of the neck, the loop being pivotally secured to the neck for swinging across the end thereof, the outer face of the cap having a central depression, the loop being bent into said depression for swivelly engaging the cap, the receptacle having a shoulder at the base of the neck positioned to limit the swinging of the cap in the loop, and the transverse thickness of the neck being sufficient to prevent disengagement of the cap from the loop at such limit of swing.

5. In combination with a receptacle having a hollow body and an apertured neck extending therefrom, the end of said neck being spherically rounded, a concave cap adapted for seating upon the rounding end of said neck, a wire loop extending from the neck over the cap, said cap being of different thicknesses at its different axial sections and being swivelly engaged by the loop to permit rotation about its axis for securement between said loop and the end of the neck, the loop being pivotally secured to the neck for swinging across the end thereof, and the dimensions of the neck being sufficient to prevent disengagement of the cap from the loop throughout such swinging movement.

In testimony whereof I have hereunto set my hand at Chicago, Illinois, this 2nd day of October, 1911.

CHAS. H. EDER.
